UNITED STATES PATENT OFFICE

JOHN M. AUFIERO, OF BROOKLYN, NEW YORK, ASSIGNOR TO E. A. LABORATORIES, INC.,
OF BROOKLYN, NEW YORK, A CORPORATION OF NEW YORK

DESIGN FOR A COVER PLATE FOR SOUND-WAVE APPARATUS OR SIMILAR ARTICLE

Application filed November 29, 1929. Serial No. 33,580. Term of patent 14 years.

To all whom it may concern:

Be it known that I, JOHN M. AUFIERO, a citizen of the United States, residing at Brooklyn, in the county of Kings and State of New York, have invented a new, original, and ornamental Design for a Cover Plate for Sound-Wave Apparatus or Similar Article, of which the following is a specification, reference being had to the accompanying drawing, forming a part thereof, wherein:

Figure 1 is a front view of a cover plate showing my new design, and

Figure 2 is a partly sectional side elevation taken along the lines 2—2 in the direction of the arrows of Figure 1.

I claim:

The ornamental design for a cover plate for sound wave apparatus or similar article, as shown.

JOHN M. AUFIERO.
